DISCHARGE GATE MECHANISM FOR CONCRETE TRANSPORTATION CONDUITS

Edwin Alvin Carl Eickstaedt, West Allis, Wis., assignor to Chain Belt Company, Milwaukee, Wis., a corporation of Wisconsin

Application May 1, 1936, Serial No. 77,422

6 Claims. (Cl. 138—47)

This invention relates to discharge gate mechanism for concrete transportation conduits, and has for one of its objects to provide mechanism of this character which will be simple in construction, comparatively inexpensive to manufacture, and highly efficient in use. The invention relates generally to the type of gate disclosed in the prior U. S. Patent No. 2,021,108, granted November 12, 1935, on an application filed by Charles I. Longenecker; and more specifically, to mechanism for retaining the gate in closed position.

With the above and other objects in view which will appear as the description proceeds, the invention consists in the novel details of construction and combinations and arrangements of parts more fully hereinafter described and particularly pointed out in the appended claims.

Referring to the accompanying drawings forming a part of this specification in which like reference characters designate like parts in all the views—

Figure 1 is a side elevational view of the discharge gate and associated mechanism constructed in accordance with the present invention, the gate being shown in closed position;

Figure 2 is a central longitudinal sectional view of the parts shown in Figure 1, the clamping mechanism, however, being shown in unlocked position and the gate partially open;

Figure 3 is a side elevational view similar to Figure 1, with parts broken away and omitted for the sake of clearness, and showing the gate in completely open position, and

Figure 4 is a transverse sectional view taken approximately on the plane indicated by the line 4—4 of Figure 1, looking in the direction of the arrows.

The gate structure generally is, or may be, of substantially the same construction as that set forth in the said Longenecker Patent No. 2,021,108, comprising a frame member 10 which is rigidly secured to conduit sections 11 as by welding or in any other suitable manner. The lower portion of the frame member is cut away as at 12 to provide a discharge opening for the concrete mixture, which opening may, if desired, be closed by gate member 13 which is pivotally hung on the conduit 11 by means of the arms 14 engaging the rod or pipe 15 which is secured to the said conduit. The said gate member 13 is preferably provided with the rubber gasket or other packing member 16 arranged to seal the joint between the gate, the frame 10 and the conduit

sections 11 in substantially the same manner as set forth in said Longenecker patent.

The frame member 10 is provided with the spaced U-shaped ears 20 in which are journalled the bearing portions 21 of shaft 22. The said shaft is provided beyond the bearing portions 21 with the eccentrically disposed studs or projections 23 and with the squared extensions 24, which latter receive the operating handles 25. A stirrup member 26 of substantially U-shape is journalled upon the eccentric studs 23 with its legs passing down to either side of the frame member 10 in relative close proximity thereto, as will be clear from Figure 4. The said stirrup 26 is preferably provided at its bottom with a transverse brace 15 bar 27 which is arranged to engage with a member carried by the gate 13 as will appear more fully below.

Bolts 28 are passed through the upstanding legs of the U-shaped journals 20 of the frame 20 member and serve to retain the shaft 22 in position, as will be readily understood from the drawings.

The gate member 13 has secured to its bottom a transversely extending substantially T-shaped bar 30, the lower surface of which, 31, is adapted to engage with the upper surface, 29, of the brace bar 27, as shown in Figures 1 and 2. The said member 30 may be provided with the extension 32, also engageable with the bar 27, and serving 30 as a stop to properly position the stirrup 26 relative to the gate when the latter is to be closed and clamped in such position.

The member 30 is also provided at one side with a finger or projection 35, the under surface of 35 which is adapted to ride upon the top surface 29 of the stirrup bar 27 as the stirrup is swung about the eccentric member 23 to clear the gate and permit the latter to drop.

With the parts in the positions illustrated in Figure 1, the discharge opening 12 is closed by the gate 13 and the plastic concrete mixture will pass through the conduit 11 just as though the latter were a solid pipe. However, if it be desired to discharge mixture through the opening 12 the handles 25 are grasped and moved through an arc of 180° to the position shown in Figures 2 and 3. This movement will lower the eccentric portions 23 of the shaft 22 and inasmuch as the stirrup 26 is hung upon these eccentrics the said stirrup will be permitted to drop a distance equal to the eccentricity of the members 23. This in turn will permit the gate 13 to drop to substantially the position shown in Figure 2, after which the operator grasps the stirrup 26 and swings it 55

in a clockwise direction as viewed in Figure 2 to substantially the position indicated in broken lines in the said figure. During this swinging movement the top surface of the stirrup bar 27 5 will slide along the under surface of the finger or projection 35 thus supporting the gate during this movement, and not only preventing its irregular lower surface from catching upon the stirrup, but also preventing the gate from dropping 10 ping unexpectedly and possibly injuring the hands of the operator as he moves the stirrup. When the stirrup has been moved to substantially the broken line position shown in Figure 2 the gate 13 will then drop to the position indicated in 15 Figure 3, whereupon plastic mixture moving through the conduit 11 may be freely discharged through the opening 12. When the discharge is completed the opening may be again closed by reversing the procedure just described.

20 With the gate 13 in open position shown in Figure 3, if it be desired to discharge the concrete into a hopper, trough, or chute, such device, indicated at 36 in Figure 3, may be supported upon a hook 37 which may be secured in an aperture 25 38 provided in the lower portion of the stirrup 26, as will be readily understood.

While one form of the invention has been illustrated and described it is obvious that those skilled in the art may vary the details of construction as well as the precise arrangement of parts without departing from the spirit of the invention, and therefore it is not wished to be limited to the above disclosure except as may be required by the claims.

35 What is claimed is:

1. Mechanism for closing a lateral discharge opening in a conduit, comprising a gate member mounted on said conduit for movement to and from said opening; a stirrup member pivotally 40 carried by said conduit for engagement with and disengagement from said gate member, said stirrup being also arranged for rectilinear clamping movements; and eccentric means for moving said stirrup rectilinearly to cause it to clamp said gate member in closing position.
2. Mechanism for closing a lateral discharge opening in a conduit, comprising a gate member mounted on said conduit for swinging movements to and from said opening; a shaft journaled on 50 said conduit, said shaft having eccentric portions; a stirrup member journaled on said eccentric portions, whereby it may be swung into and out of engagement with said gate member; and means for moving said shaft and eccentric portions to

cause said stirrup to clamp said gate member in closing position.

3. Mechanism for closing a lateral discharge opening in a conduit, comprising a gate member mounted on said conduit for swinging movements to and from said opening; U-shaped members carried by said conduit; a shaft journaled in said U-shaped members, said shaft having a pair of eccentric projections; bolts passing through the legs of said U-shaped members for retaining said shaft in position; a stirrup member journaled on said eccentric projections for swinging movements into and out of engagement with said gate member; and means for rocking said shaft and eccentric projections to cause said stirrup to clamp said gate member in closing position, and to release the same.

4. Mechanism for closing a lateral discharge opening in a conduit, comprising a gate member mounted on said conduit for swinging movements to and from said opening; a stirrup member mounted on said conduit for swinging movements relative to said gate member; means carried by said gate member for engaging with and positioning said stirrup relative to the gate when the latter is to be closed; and means for moving said stirrup to cause it to clamp said gate in closing position.

5. Mechanism for closing a lateral discharge opening in a conduit, comprising a gate member mounted on said conduit for swinging movements to and from said opening; a stirrup member mounted on said conduit for swinging movements relative to said gate member; means carried by said gate engageable with said stirrup during the swinging movements of the latter, whereby the stirrup may support the gate and prevent swinging of the latter until the stirrup is clear thereof; and means for moving said stirrup to cause it to clamp the gate in closing position.

6. Mechanism for closing a lateral discharge opening in a conduit, comprising a gate member mounted on said conduit for swinging movements to and from said opening; a stirrup member mounted on said conduit for swinging movements relative to said gate member; means carried by said gate member for engaging with and positioning said stirrup relative to the gate when the latter is to be closed, said means having a projection engageable with the stirrup during the 45 swinging of the latter, whereby the gate will be supported by the stirrup until the latter is clear; and means for moving said stirrup to cause it to clamp said gate in closing position.

EDWIN ALVIN CARL EICKSTAEDT. 55.
